G. S. WELLING.

SEWING MACHINE NEEDLE THREADER.

APPLICATION FILED JAN. 19, 1917.

1,260,611.

Patented Mar. 26, 1918.

UNITED STATES PATENT OFFICE.

GREENWOLDT S. WELLING, OF SIOUX CITY, IOWA.

SEWING-MACHINE-NEEDLE THREADER.

1,260,611.

Specification of Letters Patent. Patented Mar. 26, 1918.

Application filed January 19, 1917. Serial No. 143,392.

To all whom it may concern:

Be it known that I, GREENWOLDT S. WELLING, a citizen of the United States, and a resident of Sioux City, in the county of 5 Woodbury and State of Iowa, have invented certain new and useful Improvements in Sewing-Machine-Needle Threaders, of which the following is a specification.

The present invention relates to mechanical means for threading needles, and more particularly sewing-machine needles.

The invention has for its primary object the production of a device automatically actuated by a moving member of a sewing- 15 machine to thread the needle thereof.

Another object of the invention is the production of a sewing-machine needle embodying an element carrying a needle-threading member and reciprocated by and trans- 20 versely of the needle-bar.

The invention has for its primary object the production of an improved sewing-machine needle threader embodying a threading arm pivoted to swing toward and from 25 the needle and actuated by reciprocation of the needle bar.

Still another object of the invention is the production of a needle-threader for sewing-machines instantly adjustable to operative 30 and inoperative positions, and adapted when in the latter position to automatically reciprocate a threading hook through the needle eye.

The invention has for a further object the production of a sewing-machine needle-threader simple and inexpensive in construction and thoroughly efficient in operation.

With these and several other objects in view, the invention consisting in the construction, combination and novel arrangement of parts, will be fully understood from the following description, reference being had to the accompanying drawings, which form a part of this application and in which 45 like characters of reference indicate corresponding parts throughout the several views, of which—

Figure 1 is a front elevation of the head of a sewing-machine equipped with the preferred embodiment of the invention, parts being cut away and the threader in operative position;

Fig. 2 is a similar view, with the threader in position to be reciprocated;

Fig. 3 is a side elevation of the same, with 55 the threader in inoperative position;

Fig. 4 is a horizontal section taken on the line 4—4 of Fig. 3;

Fig. 5 is an enlarged section of the threader, taken on the line 5—5, of Fig. 4, 60 the swinging arm being cut away;

Fig. 6 is an enlarged inverted perspective view of the head of the threader arm;

Fig. 7 is an enlarged end elevation of the threading fork;

Fig. 8 is an enlarged plan of the same;

Fig. 9 is an enlarged longitudinal section of the same; and

Fig. 10 is a front elevation of the threading arm cam and parts associated therewith. 70

Although I have illustrated and herein-after described the preferred embodiment of the invention, I would not be understood as being limited to the specific structure chosen for illustration for various alterations and 75 modifications may be made in the details of construction and arrangement of parts, without departing from the spirit and scope of the invention as defined in the appended claims. 80

Referring now, to the illustrations, 11, is the head of a sewing machine, within and below which reciprocates the usual needle-bar, 12, carrying the needle 13.

At the side and adjacent the lower end of 85 the machine head is a short horizontal rock shaft, 14, pivoted to suitable supporting means, as lugs, 15, threaded into the head and having flattened ends which serve as bearings, 16, in which are journaled the 90 shanks of screws, 17, threaded into the ends of the shaft, 14.

Extending freely through the shaft is a depending rod, 18, having a head, 19, at its upper end which engages the shaft to support the rod. The said head is preferably a knurled nut threaded on the rod and having transverse grooves, 20, in its face. The said grooves intersect each other at right angles, (Fig. 6) and are curved to conform substantially to the periphery of the shaft, 14, to permit the nut to be seated in either of two positions, on the shaft, each at right-angles to the other, and prevent its turning from 100

either of said positions unless moved from the shaft.

The rod, 18, is encircled by a collar, 21, adjustably secured thereon by a set-screw, 5 22, and carrying a lateral arm, 23, the function of which will be later described. Between the collar 21, or other suitable shoulder and the shaft, 14, is interposed a compression-spring, 24, which holds the head of 10 the rod yieldably seated.

The lower end of the rod is provided with an arm 25, disposed extending in the same radial plane as the arm, 23. The end of the arm, 25, is split vertically and incloses a 15 threading hook, 26, the shank of which is clamped firmly within the split portion by means of a collar, 27, encircling said portion and secured thereon by a set-screw, 28. The said end portion is spread forming a V-shaped fork with the threading hook between the arms thereof. The forward fork arm is provided with a notch, 29, and the companion arm is split horizontally, the upper portion being bent upwardly to afford a 20 retaining member, 30. At the point of convergence of the retaining arm, 30 and the arm below it, is a transverse notch 31, registering with the notch, 29. In operation, the needle is received in the fork and the hook 25 penetrates the eye of the needle as shown in Fig. 9. The thread, 32, is then placed across the fork and in the notches and as the hook reciprocates a bight of the thread is drawn through the needle eye.

35 In holes, 33, in opposite sides of the machine head, is slidably mounted a plunger-rod, 34, having a shoulder, 35, between which and the wall of the head is interposed a compression-spring, 36, which tends to force the 40 plunger toward the shaft, 14. The plunger is provided with a head, 37, engaging a cam, 38, carried by the shaft, 14.

The cam is provided with three flat faces, 39, 40 and 41. The face, 41 coacts with the 45 plunger to hold the thread arm in normal, or inoperative position, in which position the rod, 18, is swung upwardly with the arm, 25, extended rearwardly, as shown in Fig. 3.

When the threader is swung downwardly 50 to its operative position, the plunger coacts with the cam face, 39, to force the arm, 25, toward the needle, the threader being held out of the path of the needle by engagement of the arm, 23, with the needle-bar. On the 55 upward stroke of the needle-bar, the arm, 23, enters a hole, 42, in the needle bar, permitting the arm, 25, to move to the extremity of its stroke with the prongs or arms of the threader fork on opposite sides of the needle. 60 The thread is then placed across the fork as previously stated. As the stroke of the needle-bar is continued, the threader is also carried upwardly, this being permitted by the spring, 24. The downward stroke of the 65 needle-bar forces the arm 23, from the open-

ing 42, thereby withdrawing the threader with a bight of thread. The threader will then be swung to the position indicated in broken lines in Fig. 2, in which position it is yieldably held by engagement of the cam 70 face, 40, with the plunger. The threader may then be swung upwardly to its inoperative position.

Obviously, the collar, 21, is adjustable to regulate the position of the arm, 23, so 75 that when the latter enters the opening 42, the threading-hook will be alined with the eye of the needle.

Having thus described my invention, what I claim is new and desire to secure by Letters Patent of the United States, is—

1. A needle-threader for a sewing-machine including a moving part and a needle, comprising a threading element operable to penetrate the needle eye, governed by said 85 part, and movable during its operation a distance with the needle during the latter's stroke.

2. A needle-threader for a sewing-machine including its needle-bar and needle, comprising a member mounted to move toward and from the needle, a threading element on said member adapted to penetrate the needle-eye when said member is moved toward the needle, said member being also 95 movable vertically, and means operable to move said members vertically with the needle, whereby the threading element may penetrate the needle eye while the needle is moving.

3. A needle-threader for a sewing machine including its needle-bar and needle comprising a member mounted to move toward and from the needle, a threading element on said member adapted to penetrate 105 the needle-eye when said member is moved toward the needle, said member being also movable vertically, and means governed by the needle-bar for moving said member vertically with the needle while the threading element is penetrating the needle-eye.

4. A needle-threader for a sewing machine including its needle-bar and needle comprising a member mounted to move toward and from the needle, a threading element on said member adapted to penetrate 115 the needle-eye when said member is moved toward the needle, said member being also movable vertically, and means governed by the needle-bar for moving said member toward and from the needle and vertically with the needle.

5. A needle-threader for a sewing machine including its head, needle, and a moving part, comprising a member adapted to 125 be mounted on the head to move toward and from the needle, a threading element adapted to penetrate the needle-eye when said member is moved toward the needle, said member being also movable vertically, and 130

- means controlled by said part for moving said member vertically with the needle when the threading element penetrates the needle-eye.
5. 6. A needle-threader for a sewing-machine including its needle-bar and needle comprising an arm swinging transversely to the needle and provided with a threading element adapted to penetrate the needle-eye, yieldable means operable to swing said arm toward the needle, means controlled by the needle-bar for holding the arm from the needle and means controlled by the needle-bar for releasing the latter means.
10. 7. A needle-threader for a sewing machine including its needle-bar and needle, comprising a member yieldably impelled toward the needle, a threading hook thereon to penetrate the needle-eye, and means controlled by the needle-bar for alternately forcing the said member from the needle-bar and releasing said member, whereby the hook is reciprocated through the needle-eye.
15. 8. A needle-threader for a sewing-machine including its head, needle-bar and needle, comprising a threading arm adapted to be pivotally mounted on the side of the head and depend therefrom to swing toward and from the needle, a threading element carried by the arm to penetrate the needle eye, yieldable means impelling the arm toward the needle, a laterally extending part on said arm engaging with the needle-bar to hold the threading element from the needle and means controlled by movement of the needle-bar to release said part when the needle eye is alined with said element.
20. 9. A needle-threader for a sewing-machine including a head, needle-bar and needle, comprising a rod adapted to be pivotally mounted on the side of the head and swing in a vertical plane toward and from the needle-bar, said rod having a lower lateral arm provided with a threading element to penetrate the eye of the needle, yieldable means impelling said rod toward the needle-bar, and a second lateral arm carried by said rod and engageable with the needle-bar to hold said element from the needle, the
25. 45. 50. 55. 60. 65. 70. 75. 80. 85. 90. 95. 100. 105. 110. 115. 120. 125. 130. 135.
- needle-bar having a recess positioned to receive said second arm to permit movement of the rod toward the needle-bar when the needle-eye is alined with said element.
10. A needle-threader for a sewing-machine including a head, needle-bar and needle, comprising a rod adapted to be pivotally mounted on the side of the head and swing in a vertical plane toward and from the needle-bar, said rod having a lower lateral arm provided with a threading element to penetrate the eye of the needle, yieldable means impelling said rod toward the needle-bar, and a second lateral arm on said rod adjustable longitudinally thereof and engageable with the needle-bar to hold said

element from the needle, the needle-bar having a recess positioned to receive said second arm to permit movement of the rod toward the needle-bar when the needle-eye is alined with said element.

11. A needle-threader for a sewing machine including its needle-bar and needle, comprising a member movable toward and from the needle, a threading hook thereon to penetrate the needle eye, said member being yieldable upwardly, and means controlled by the needle-bar for moving the said member toward and from the needle and coincidentally forcing the member upwardly with the needle.

12. The combination with a sewing-machine including its head, needle-bar and needle, of a horizontal rock shaft pivotally mounted on the side of the head, a rod extending freely therethrough and having a lateral arm disposed toward the needle, a threading element carried by said arm to penetrate the needle eye, means controlled by reciprocation of the needle-bar for rocking said shaft and a head on the upper end of said rod adapted to engage the shaft to support the rod and prevent turning thereof.

13. The combination with a sewing-machine including its head, needle-bar and needle, of a threader including a horizontal rock-shaft pivotally mounted on the side of the head, a rod freely extending therethrough, a lateral arm carried by said rod disposed toward the needle and having a threading element to penetrate the eye of the needle, a head on the end of said rod to engage the shaft to support the rod, yieldable means impelling said rod toward the needle-bar and a second arm of said rod engageable with the needle-bar to hold the threading element from the needle, the needle-bar having a recess positioned to admit said second arm when the needle eye is alined with the threading element during the upward stroke of the needle-bar.

14. The combination with a sewing-machine including its head, needle-bar and needle, of a needle threader comprising a horizontal rock shaft pivotally mounted on the side of the head, a rod freely extending therethrough, a head on the end of said rod engaging the shaft to support the rod, a shoulder on the rod below the shaft, yieldable means interposed between the shaft and shoulder, a lateral arm on said rod extending toward the needle, a threading element carried by said arm to penetrate the needle eye, yieldable means impelling the rod toward the needle-bar and a second arm on the rod engageable with the needle-bar to hold said element from the needle, the needle-bar being recessed to admit said second arm when the needle eye is alined with the threading element during the upward stroke of the needle-bar.

15. The combination with a sewing-machine including its head, needle-bar and needle, of a horizontal rock-shaft pivotally mounted on the side of the head, a rod extending laterally and freely therethrough, a lateral arm on said rod, a threading element carried thereby to penetrate the needle-eye, means for holding the head of the rod in yieldable engagement with the shaft, the head of the rod and the shaft being mutually engageable to hold the rod against turning from either of two positions except by disengagement of the head of the rod from the shaft, each of said positions being at right angles to the other, yieldable means impelling the rod toward the needle bar and a second arm on the rod engageable with the needle-bar to hold the threading element from the needle, the needle-bar being recessed to receive said second arm when the needle eye is alined with the threading element during the upward stroke of the needle-bar.

16. The combination with a sewing-machine including its head, needle-bar and needle, of a needle threader including a horizontal rock-shaft pivotally mounted on the side of the head, a cam carried by the shaft, a rod depending from the shaft, a lateral arm on the rod disposed toward the needle bar, a threading element carried by the arm to penetrate the needle eye, a yieldable plunger mounted in the head to co-act with the cam and rock shaft to impel the rod toward the needle bar and a second arm on the rod engageable with the needle-bar to hold the threading element from the needle, the needle-bar being recessed to receive said second arm when the needle eye is alined with the threading element during the upward stroke of the needle-bar.

17. The combination with a sewing machine including its head, needle bar and needle, of a needle threader comprising a horizontal rock shaft mounted on the side of the head, a cam mounted on said shaft, a rod depending from said shaft, an arm on the rod extending toward the needle-bar, a threading element carried by the arm to penetrate the needle-eye, a yieldable plunger mounted in the head, the cam having a face engageable with the plunger to force the rod toward the needle-bar and a second arm on the rod engageable with the needle bar to hold the threading element from the needle, the needle-bar being recessed to receive said second arm when the needle eye is alined with the threading element during the upward stroke of the needle bar, the rod being adapted to be swung to substantially an inverted position and the cam having a face engageable with the plunger to hold the rod in said inverted position.

18. The combination with a sewing machine including its head, needle-bar and

needle, of a needle threader comprising a horizontal rock-shaft pivotally mounted on the side of the head, a cam mounted on the rock-shaft, a yieldable plunger mounted in the head, a rod extending freely laterally through said shaft, a head on the end of the rod to engage the shaft and provided with a groove conforming to the shape of the shaft to prevent turning of the rod without disengagement of the head thereof from the shaft, a shoulder on the rod on the opposite side of the shaft, yieldable means interposed between the shaft and said shoulder, an arm on the rod directed toward the needle-bar, a threading element carried thereby to penetrate the needle-eye, the cam having a face engageable with the plunger to impel the rod toward the needle-bar and a second arm on the rod engageable with the needle-bar to hold the threading element from the needle, the needle-bar being recessed to receive said second arm when the needle eye is alined with the threading element during the upward stroke of the needle-bar.

19. A needle-threader for a sewing machine including its head, and needle, comprising a cam-shaft adapted to be mounted on the side of the head, an arm carried by the cam-shaft and adapted to be swung upwardly adjacent the head and downwardly, a threading element carried by the arm to penetrate the needle-eye, and yieldable means engageable with the cam to impel the arm toward the needle when the arm is swung downwardly.

20. A needle-threader for a sewing machine including its head, and needle, comprising a cam-shaft adapted to be mounted on the side of the head, an arm carried by the cam-shaft and adapted to be swung upwardly adjacent the head and downwardly, a threading element carried by the arm to penetrate the needle-eye, and yieldable means engageable with the cam to impel the arm toward the needle when the arm is swung downwardly and prevent retrograde movement of the arm when swung upwardly.

21. A needle-threader for a sewing machine including its head and needle, comprising a cam-shaft adapted to be mounted on the head, an arm carried by the cam-shaft and adapted to be swung upwardly adjacent the head, and downwardly, a threading element carried by the arm to penetrate the needle-eye, and a plunger adapted to be yieldably mounted in the head to engage the cam to impel the arm toward the needle.

22. A needle-threader for a sewing machine including its needle-bar and needle, comprising a member yieldably impelled toward the needle, a threading element carried thereby to penetrate the needle-eye and an arm on said member engageable with the

needle-bar to hold the member from the needle, the needle bar having a recess to receive the arm to permit the member to be moved toward the needle.

5 23. A needle-threader for a sewing-machine including a needle-bar member and a needle, comprising a member yieldably impelled toward the needle, a threading element thereon to penetrate the needle-eye,

and an arm on one of said members engageable with the other member to hold said second member from the needle, the unarmed member having a recess to receive the arm to permit the said second member to be moved toward the needle. 10

In testimony whereof, I have hereunto set my hand this 17th day of January, 1917.

GREENWOLDT S. WELLING.
